UNITED STATES PATENT OFFICE.

STEPHEN D. LAYMAN AND HANS C. HANSEN, OF BOSTON, MASSACHUSETTS.

PERFORATING-MACHINE.

SPECIFICATION forming part of Letters Patent No. 354,913, dated December 28, 1886.

Application filed February 17, 1886. Serial No. 192,201. (No model.)

To all whom it may concern:

Be it known that we, STEPHEN D. LAYMAN and HANS C. HANSEN, both citizens of the United States, and residing at Boston, in the 5 county of Suffolk and State of Massachusetts, have jointly invented certain new and useful Improvements in Pin-Hole-Perforating Machines; and we do hereby declare that the same are fully described in the following specification, and illustrated in the accompanying drawings.

This invention relates to improvements in pin-hole-perforating machines, for the purpose of perforating sheets of paper, bristol-board, 15 paper-board, and similar articles in one or more rows, parallel or crossing each other, according to the use for which the perforated article is intended.

The invention is carried out as follows, reference being had to the accompanying drawings, where—

Figure 1 represents a plan view, and Fig. 2 represents a side elevation, of the improved machine. Fig. 3 represents an enlarged cross-section on the line A B, shown in Fig. 1, and Fig. 4 represents an enlarged vertical section on the line C D, also shown in Fig. 1. Fig. 5 represents a modification of the machine as adapted for perforating the paper, &c., simultaneously with two or more parallel rows of holes.

Similar letters refer to similar parts wherever they occur on the different parts of the drawings.

35 *a* represents the table-top or work-supporting plate of the machine, preferably provided with a base frame or support, *a'*, on its under side, that may be secured in a suitable manner to a bench or table, as may be found 40 most convenient. To the table-top *a* or its base *a'* is cast in one piece or secured in a suitable manner the goose-neck *b*, having front and rear bearings, *b'* and *b''*, for the shaft *c*, as shown in Figs. 1, 2, 3, and 4. To the rear end 45 of shaft *c* is secured the fast pulley *d*, by means of which and a belt carried from a rotary pulley a rotary motion is imparted to said shaft *c*. *d'* is a loose pulley on shaft *c*, as usual.

In front of bearing *b'* is secured to shaft *c* 50 the punch-wheel *E*, having its outer cylindrical portion made in the form of an annular

rim, *e*, between which and the annular projection *e'* is made an annular groove, *e''*, as shown in Figs. 3 and 4. The rim *e* is provided with a number of radial perforations, in 55 which are inserted the punches *e³* *e³*, that project a little outside of the outer periphery of punch-wheel *E*, as shown in Figs. 3 and 4, and have their inner ends resting against the annular projection or shoulder *e'*, as shown in 60 said figures. After the punches *e³* *e³* have been inserted through the perforations in rim *e* they are secured in place by means of a solder or alloy or molten metal, *e⁴*, run into the groove *e''*, as shown in Figs. 3 and 4. By 65 having the punch-wheel *E* arranged upon shaft *c* outside of the bearing *b'* papers of any width can be fed to the perforating device with greater freedom, as compared with machines in which such punch-wheel is located between 70 two bearings.

Below the rotary punch-wheel *E* is located the die-wheel *F*, which latter is secured to the shaft *f*, as shown in Figs. 3 and 4. *f'* is an annular rim at the periphery of the die-wheel 75 *F*, which rim is provided with a series of perforations, *f''* *f''*, corresponding in number and size to the punches *e³* *e³*, as shown in said Figs. 3 and 4. As the punch-wheel *E* is rotated its punches *e³* *e³* are caused to enter, just a little, 80 the perforations on the rim of the die-wheel *F*, and in this manner a positive motion is imparted to the die-wheel *F* from the punch-wheel *E*.

f³ *f³* are the ends or trunnions of the shaft *f*, 85 and they are free to rotate in bearings *g* *g*, secured in a suitable manner to the under side of table-top *a* or supports *a'*. The trunnions *f³* *f³* of the shaft *f* are free to move longitudinally in their bearings *g* *g*, to permit the die-wheel *F* to adjust itself automatically and longitudinally to any inequalities in the position and arrangement of the punches *e³* *e³*.

If so desired, the shaft *f* may be made stationary and the die-wheel arranged to run 95 and slide freely upon said shaft to equal advantage. This is a very essential feature, as it is very difficult to arrange the punches *e³* mathematically correct on the wheel *E*, one in relation to the others; and as it is equally difficult to drill the perforations *f''* *f''* mathematically correct and in a line with each other, 100

we so arrange the die-wheel F in its bearings that it shall be free to adjust itself longitudinally in relation to the punch-wheel E.

g' g' are screws by means of which the bearings g g are secured to the support a' below the table a, as shown in Figs. 3 and 4. The bearings g g are preferably made as two independent parts that are secured together by means of set-screws g" g", (shown in dotted lines in Fig. 4,) after the trunnions f' f' of the shaft f have been located in the holes in said bearings. a" is a slot through the table-top a, into which a portion of the die-wheel F projects as it rotates, and receives the punches e' e' into its perforations f" f" during the rotation of the punch-wheel E.

H is a vertically-adjustable guide-plate having a slotted opening, h, for the punch-wheel E to pass through, as shown in Figs. 3 and 4, which guide-plate, after being adjusted so as to leave a little space between its under side and the top of table a for the material to pass through, is secured to one side of bearing b' by means of set-screws h' h', passing through slot-holes in the vertical upward extension H' of the said guide-plate H, as shown in dotted lines in Fig. 4.

The object of the guide-plate H is to prevent the paper or material that is being perforated from being carried around the punch-wheel E and to guide it forward in a straight line on the table a. The guide-plate H is made vertically adjustable, so as to compensate for differences in thickness of materials that are to be perforated.

I is a paper-gage arranged on top of table a at a right angle to the shaft c, and it is made adjustable to and from the punch and die wheels E and F by means of set-screw or thumb-nut i, the head of which is guided in the groove a', made in the upper side of table a, as shown in Fig. 1. For the purpose of guiding said gage I accurately during its adjustment to and from the punch and die wheels E F, we provide it near its ends with guide-blocks i' i', adapted to slide in parallel grooves a' a' in table a, as shown in said Fig. 1, such gage being similar in construction and operation to the adjustable work-rests used on circular-saw benches.

The operation is as follows: The shaft c and its punch-wheel E are set in a rotary motion, and as the punches e' e' enter the perforations f" f" on the die-wheel F the latter are set in a positive rotary motion corresponding to that of the punch-wheel E. The paper to be per-

forated is then introduced at x between the under side of the guide H and top of table a and fed forward until its front end is taken hold of by the punches e' e' and the die-wheel F and caused to move onward and to be perforated by the punches e' e', passing through the paper and entering the perforations f" f" in the die-wheel F. During such operation one edge of the paper or material is guided against the gage I, which is set and adjusted at a proper distance from the punch and die wheels, according to the distance the row of perforations is to be made from one edge of the paper.

In Fig. 5 is shown a modification of our invention as adapted for perforating the paper at one operation with a number of parallel lines of perforations, for which purpose a series of punch-wheels, E E, are secured at a proper distance apart on the rotary shaft c, each punch-wheel being constructed as hereinabove fully described, and having arranged below it and the table a the die-wheel F, located in bearings g g, precisely in the same manner as shown in Figs. 3 and 4, the die-wheels being free to move in the direction of their shafts, to compensate for inaccuracies in the location of the punches and the perforations on the respective punch and die wheels E and F.

This machine is very simple in its construction and accurate in the execution of the work, on account of the longitudinally self-adjusting or "floating" die-wheel by which the punches and perforations on the respective punch and die wheels are made to coincide.

Having thus fully described the nature, construction, and operation of our invention, we wish to secure by Letters Patent, and claim—

In a perforating-machine, the rotary punch-wheel E, having radial punches e' e', combined with the peripherally-perforated die-wheel F, secured to shaft f, the latter being free to adjust itself longitudinally in the bearings g g, so as to enable the die-wheel to adjust itself automatically in relation to the punches on the punch-wheel during the rotation of the latter, as herein set forth and described.

In testimony whereof we have affixed our signatures in presence of two witnesses.

STEPHEN D. LAYMAN.
HANS C. HANSEN.
